UNITED STATES PATENT OFFICE.

ARTHUR W. OWEN, OF WINSTED, CONNECTICUT, AND GEORGE B. OWEN, JR., OF NEW YORK, N. Y., ASSIGNORS TO THE WM. L. GILBERT CLOCK COMPANY, OF WINSTED, CONNECTICUT, A CORPORATION OF CONNECTICUT.

DESIGN FOR A CLOCK-CASE.

No. 37,642.

Specification for Design.

Patented Nov. 7, 1905.

Application filed August 16, 1905. Serial No. 274,481. Term of patent 7 years.

To all whom it may concern:

Be it known that we, ARTHUR W. OWEN, residing at Winsted, in the county of Litchfield and State of Connecticut, and GEORGE B. OWEN, Jr., residing at New York, in the county and State of New York, citizens of the United States, have invented a new, original, and ornamental Design for Clock-Cases, of which the following is a specification, reference being had to the accompanying drawing, forming part thereof.

The figure is a plan view of a clock-case, showing our new design.

We claim—
The ornamental design for a clock-case, as shown.

ARTHUR W. OWEN.
GEO. B. OWEN, JR.
